US0D1001794S

(12) **United States Design Patent** (10) **Patent No.:** **US D1,001,794 S**
(45) **Date of Patent:** **** Oct. 17, 2023**

(54) **PHONE HOLDER**

(71) Applicant: **Benzhi (Shenzhen) Information Technology Co., Ltd.**, Guangdong (CN)

(72) Inventor: **Xihong Chen**, Shenzhen (CN)

(73) Assignee: **BENZHI (SHENZHEN) INFORMATION TECHNOLOGY CO., LTD.**, Guangdong (CN)

(**) Term: **15 Years**

(21) Appl. No.: **29/779,746**

(22) Filed: **Apr. 21, 2021**

(30) **Foreign Application Priority Data**

Oct. 22, 2020 (CN) 202030629616.1

(51) **LOC (14) Cl.** **14-06**
